His Attorney

UNITED STATES PATENT OFFICE.

ALFRED N. GOLDSMITH, OF NEW YORK, N. Y., ASSIGNOR TO GENERAL ELECTRIC COMPANY, A CORPORATION OF NEW YORK.

SIGNALING SYSTEM.

1,404,756.

Specification of Letters Patent. Patented Jan. 31, 1922.

Application filed May 9, 1918. Serial No. 233,561.

To all whom it may concern:

Be it known that I, ALFRED N. GOLDSMITH, a citizen of the United States, residing at New York, in the county of New York, 5 State of New York, have invented certain new and useful Improvements in Signaling Systems, of which the following is a specification.

My present invention relates to signaling 10 systems and more particularly to the controlling of the amplitude of the current supplied from a high frequency source to a radiating antenna system for the purpose of transmitting signals.

15 In case an oscillating loop circuit is supplied by a constant potential generator it is well known that a variation of the resistance of the loop will not appreciably change the current flowing therein if the reactances 20 composing the loop are large in comparison with the resistance. Hence, it is not practical to secure an effective control of the current in such a circuit merely by varying its resistance. The object of my invention is 25 to provide an efficient way of controlling the amplitude of the current in such a circuit in accordance with variations in the amplitude of a signaling current which will not be subject to this disadvantage which is inherent in the circuit.

30 In carrying out my invention I employ a variable resistance device in series with the circuit which feeds energy to the loop circuit. My invention may be utilized in 35 a great variety of circuit organizations for transmitting various forms of signals and with different sources of radio frequency current. In case an electron discharge device of the pliotron type is employed for 40 producing oscillations the loop circuit may be the output circuit of the pliotron. In this case I insert the variable resistance device in one of the leads which supply energy to the output circuit of the pliotron.

45 The novel features which I believe to be characteristic of my invention are pointed out with particularity in the appended claims. The invention itself, however, both as to its organization and method of operation together with further objects and advantages thereof will best be understood by reference to the following description taken in connection with the accompanying draw-

ing in which I have illustrated one way of carrying my invention into effect.

55 I have indicated in the drawing a pliotron 1 comprising the usual filamentary cathode 2, anode 3 and grid 4 enclosed in an evacuated envelope. This pliotron is used for producing radio frequency oscillations. The 60 anode and grid of the pliotron are connected to a loop circuit comprising an inductance 5 and a variable condenser 6 by means of which the circuit is tuned to the frequency 65 of the oscillations which are to be produced. Energy for the operation of the oscillator is supplied by the direct current generator 7 which is connected to the cathode and anode, the cathode being grounded at 8. Condenser 9 prevents the direct current component 70 of the plate current from flowing through inductance 5. A choke coil 10 in series with the generator 7 prevents the radio frequency component of the plate current 75 from flowing through the generator 7.

75 It will usually be desirable to apply to the grid a definite potential with respect to the cathode in order to adjust the normal current through the pliotron to a point on its operating characteristic which will be most favorable for its operation. This potential, which will usually be negative but which may be either positive or negative, may be obtained from the battery 11, a radio frequency choke coil 12 being included in the circuit to prevent radio frequency currents from flowing through the battery 11. The condenser 13 will prevent the short circuiting of battery 11 through inductance 5.

85 The feed circuit for the resonant loop 90 circuit 5, 6, is completed through a second pliotron 14, the anode 15 of which is connected to a point 17 in inductance 5 and the cathode 16 of which is grounded at 18. If it is desired to modulate the radio frequency 95 output of pliotron 1 to the antenna 19 it is not possible to do so by varying the resistance of the oscillating circuit 5, 6, since with a constant potential supply the current through inductance 5 will remain substantially unchanged and hence the voltage induced in antenna 19 will not vary. For example, I have found in one case that with no resistance in the oscillating circuit the current was 2.5 amperes while with a resistance of 18 ohms the current was only reduced 100 105

to 2.1 amperes. This difficulty may be overcome, however, by varying the resistance of the feed circuit. In the arrangement shown this may conveniently be accomplished by 5 varying the resistance of pliotron 14 by varying the potential of its grid 20 in accordance with the signals to be transmitted. In the case illustrated I have shown how the radio frequency current may be modulated in 10 accordance with a telephone current from transmitter 21 which is applied to a grid circuit of pliotron 14 through a transformer 22. It will, of course, be understood that the system may equally well be employed for 15 transmitting other forms of signals by merely impressing the desired form of signaling current on the grid circuit of pliotron 14, and that my invention is not limited to the use of the particular form of variable 20 resistance shown.

The operation of the circuit which I illustrated and described may be explained somewhat as follows:

When the circuit of generator 7 is closed 25 direct current will start to flow through the pliotron 1 and at the same time a current impulse will charge the condenser 9. This will cause a current impulse to flow through the upper half of coil 5 and pliotron 14, producing 30 momentary current in circuit 5, 6. As a result the potential of the grid 4 will be changed and this change in grid potential will vary the internal resistance of the pliotron. Assume, for example, that the resistance 35 increases, that is, the grid becomes more negative. The feeding current through the choke coil 10 tends to decrease, but the decrease is opposed by the counter electromotive force across coil 10 so that the direct current 40 remains the same, but a reactance voltage builds up across coil 10. This is added to the D C potential of the generator 7, and, therefore, in effect the plate voltage of the pliotron is increased. This increase 45 in plate voltage causes a new rush of current through condenser 9 into coil 5 and pliotron 14, and a correspondingly greater current in the circuit 5, 6. This action will continue until the pliotron 1 has reached a substantially 50 infinite resistance. The action then reverses and the resistance of the pliotron decreases to a low value, when the grid 4 becomes strongly positive. In this way oscillations will be produced in the circuit 5, 6. 55 From another aspect the circuit 5, 6 may be considered as a constant resistance so related to the variable resistance of the pliotron 1 that it may periodically produce a variation in the pliotron resistance. From 60 this view the action may be considered as follows:

When the pliotron alternates in resistance the choke coil 10 keeps the direct current from the generator 7 substantially constant, 65 but the potential across the pliotron alter-

nates. Hence in effect the pliotron acts as if it were an alternating current generator having a terminal voltage which was constant over a considerable range of load.

What I claim as new and desire to secure 70 by Letters Patent of the United States, is:

1. The combination in a signaling system of an electron discharge relay having an incandescent cathode, an anode and a grid enclosed in an evacuated envelope, a source of 75 current and a high frequency choke coil connected between cathode and anode, a resonant loop circuit connected to the anode and grid of said relay in such a way that high frequency oscillations may be produced in 80 said loop circuit, a second electron discharge relay similar to the first having its anode connected to an intermediate point in the inductance of said loop circuit and its cathode connected to the cathode of the first relay, 85 and means for varying the potential of the grid of said second relay in accordance with variations in a signaling current.

2. The combination in a signaling system of an electron discharge relay having an incandescent cathode, an anode, and a grid enclosed in an evacuated envelope, a source of 90 current and a high frequency choke coil connected between cathode and anode, a resonant loop circuit comprising an inductance 95 and capacity connected in parallel to the anode and grid of said relay, a circuit connection between the cathode of said relay and an intermediate point in the inductance of said loop circuit, a second electron discharge relay similar to the first having its 100 cathode and anode included in said circuit connection, and means for varying the potential of the grid of said second relay in accordance with variations in a signaling current. 105

3. The combination in a signaling system of an electron discharge relay having an incandescent cathode, an anode, and a grid enclosed in an evacuated envelope, a resonant 110 loop circuit connected to the anode and grid of said relay in such a way that high frequency oscillations may be produced in said loop circuit, a circuit for feeding energy to said loop circuit connected to an intermediate point in the inductance of said loop circuit and including a source of direct current and a high frequency choke coil, and means for varying the resistance of said feed circuit in accordance with variations in 115 a signaling current. 120

4. The combination in a signaling system of an electron discharge relay having an incandescent cathode, an anode and a grid enclosed in an evacuated envelope, a resonant 125 loop circuit connected to said relay in such a way that high frequency oscillations may be produced therein, a circuit for feeding energy to said loop circuit connected to an intermediate point in the inductance of said 130

loop circuit and including a source of direct current and a high frequency choke coil, and means for varying the resistance of said feed circuit in accordance with variations in a 5 signaling current.

5. The combination in a signaling system of a resonant loop circuit, a circuit connected to an intermediate point in the inductance of said loop circuit and including a substantially constant potential source for feeding 10

energy to said loop circuit to produce high frequency oscillations therein, a high frequency choke coil in said circuit connection, and means for varying the resistance of said feed circuit in accordance with variations in a 15 signaling current.

In witness whereof, I have hereunto set my hand this 7th day of May, 1918.

ALFRED N. GOLDSMITH.
